UNITED STATES PATENT OFFICE

2,597,700

ELECTRIC IRON

Justice H. Beach, Canton, Ohio, assignor to The
Hoover Company, North Canton, Ohio, a cor-
poration of Ohio

Application April 3, 1951, Serial No. 218,970

10 Claims. (Cl. 219—25)

1

The present invention relates to electric smoothing irons and more particularly to a combined control and conductor cord swiveling arrangement therefor.

Specifically, according to the present invention, a conductor cord is secured to the rear of the cover shell so that it can be extended directly rearwardly from the iron or rotated to extend either to the right or left for right and left hand ironing. A thermostat control dial is rotatably mounted on the same axis beneath the hand piece of the handle in order to conserve space.

According to the present invention the iron is provided with a cantilever handle secured at its front end to the sole plate in order that the rear of the cover shell may be left free for the mounting of the control dial and conductor cord.

Other objects and advantages of the present invention will become apparent as the description proceeds when taken in connection with the accompanying drawings in which:

Figure 1 is a perspective view of the iron of the present invention; and

Figure 2 is a sectional view with certain parts broken away to show the details of construction.

Referring to the drawings, the reference numeral 10 represents a sole plate heated by an embedded electric heater 11 of known construction.

A cover shell 12 overlies the sole plate 10 and its outline follows that of the sole plate. A cantilever handle 13 is secured to the cover shell 12 in any suitable manner. The specific method of securing the handle 13 forms no part of the present invention and has therefore not been represented in any specific manner. The handle 13 includes a supporting post 14 and a horizontal extending hand piece 15 extending backwardly over the top of the cover shell and adapted to be grasped by the hand of the user. Thumb rests 53 and 54 are formed on both sides of the handle, at its forward end, for right and left hand ironing respectively.

Near its front end the cover shell 12 is secured to the sole plate 10 by a stud 16 and screw 17. At its rear end the cover shell 12 extends rearwardly of the sole plate at extension 18. A bracket 19 is welded to the inner surface of the extension 18 and is reinforced by a strut 20 as shown in Fig. 2. The bracket 19 is secured to lugs 21 extending rearwardly from the sole plate 10 by a closure plate 22. The bracket 19, strut 20 and closure plate 22 thus form the rear support for the cover shell 12.

Electric current is conducted to the heater 11 from a conductor cord 23, by conductors 24, 25,

5 terminals 26 and thermostatic switch 27. While the switch as such forms no part of the present invention, it comprises a bimetallic element 28 in heat exchange relationship with the sole plate 10. An insulating button 29 is supported in the free end of the bimetallic element 28 and coacts with the end of a spring arm 30 to open and close contacts 31 and 32 as the temperature of the sole plate rises and falls.

10 The contact 32 is mounted on the end of spring arm 33 whereby the contact 32 may be moved toward and away from the contact 31 in setting the temperature adjustment of the switch 27. A shaft 38 is screw threaded into a nut 34 supported on a 15 rigid arm 35, secured to the sole plate 10 by a screw 36 which also secures the switch to the sole plate.

The lower end of shaft 38 has an insulating button 37 which contacts the spring arm 33 to move the contact 32 away from contact 31 against the bias of spring arm 33.

20 Coacting stops 38 and 39 limit the rotation of the shaft 38 to less than 360°. A gear 40 is non-rotatably secured to the upper end of the shaft 25 38 to impart rotation thereto in adjusting the relative positions of the contacts 31 and 32. The gear 40 is intermeshed with a gear 41 which is 25 rotatably mounted on the rear cover shell 12 beneath the handle portion 15 of the handle 13.

30 A bearing sleeve 42 is secured to the cover shell 12 and rotatably receives the control sleeve 43 which has its lower end secured to the gear 41 and its upper end secured to a control knob 44 by retractable pins 45. The control knob 44 may be 35 made of insulating material as shown.

The bore of sleeve 43 forms a passage for the conductors 24 and 25 as well as a passage for a supporting pin 46 which is supported at its lower end on a forward extension of the bracket 19.

40 Rotatably mounted on the upper end of pin 46, by means of spring detent 47 and groove 48 is an insulating dome 49, which supports the conductor cord 23 for rotation to approximately 180° on either side of the iron. The conductor cord 23

45 extends through the wall of the dome 49, as shown, and is attached thereto by cord protector 50. The conductors 24 and 25 are sufficiently long to permit free rotation of the dome 49. The lower periphery of the dome 49 extends into a recess 51 in the dial 44 to prevent removal of securing pins 45 until the dome is removed. If desired depressions may be formed in the groove 48 on opposite sides to hold the conductor cord 23 either in its right or left hand position. The extension 18 of the cover shell 12 and the rear of the

hand piece 15 of the handle are so positioned as to support the iron in an inclined position on its heel.

As shown in Fig. 1 suitable indicia is inscribed on the top of the dial 44 to cooperate with a reference point 52 on the top of the cover shell 12 to indicate the control setting.

From the foregoing it can be seen that this invention provides an arrangement in which the conductor cord may be swiveled on the cover shell beneath the rear leg of the handle with the control dial rotatably mounted on the same axis thereby preserving space and presenting a neat appearance.

While I have shown and described but a single modification of my invention it is to be understood that that modification is to be taken as illustrative only and not in a limiting sense. I do not wish to be limited to the particular structure shown and described but to include all equivalent variations thereof except as limited by the scope of the claims.

I claim:

1. In an electric iron, a sole plate, a heater therefor, electrical conductors for conducting electricity to said heater, a cover shell secured to said sole plate, means for pivotally supporting said conductors on said cover shell, a thermostatic switch for controlling the supply of electricity to said heater and manually actuatable means connected to said switch for adjusting the temperature setting thereof, said manually actuatable means including a control dial rotatably mounted above said cover shell on the same axis as said pivotal conductor support.

2. In an electric iron according to claim 1 in which said conductor support includes an insulating dome pivotally mounted above said control dial and said conductors are secured to and pass through the wall of said dome.

3. In an electric iron according to claim 1 in which said control dial is rotatably secured to said cover shell by a bearing sleeve through which said conductors pass.

4. In an electric iron according to claim 3 in which said conductor support includes a supporting pin extending upwardly through said bearing sleeve and said conductor support being pivotally mounted on said pin above said control dial.

5. In an electric iron, a sole plate, a heater therefor, a thermostatic switch for controlling the flow of electricity to said heater, adjustable means for controlling the temperature setting of said switch, a cover shell secured to and overlying said sole plate, a bearing sleeve secured to said cover shell, a control sleeve swiveled on the interior of said bearing sleeve, means for driv- 60 ingly connecting said control sleeve to said adjustable means, an annular control dial secured

to the top of said control sleeve, an electric cord electrically connected to said heater and switch and extending through said control sleeve and means extending through said control sleeve for rotatably supporting said conductor cord on said cover shell.

6. In an electric iron according to claim 5 in which said supporting means comprises a pin secured to said cover shell and extending upwardly through said control sleeve and an insulating dome rotatably secured to the upper end of said pin, said conductor cord extending through and being secured to the wall of said dome with the individual conductors thereof passing through said control sleeve.

7. In an electric iron, a sole plate, a cover shell secured to and overlying said sole plate, a cantilever handle having a supporting leg secured to the front end of said cover shell and a grip portion extending backwardly therefrom, a heater for said sole plate, a thermostatic switch for controlling the supply of electricity to said heater, a conductor cord electrically connected to said switch and heater, means for pivotally supporting said conductor cord on said cover shell beneath the rear end of the grip portion of said handle, and a manually actuatable control dial connected to said switch for varying the temperature setting thereof, said control dial being supported on said cover shell to rotate on the same axis as said pivotal cord support.

8. In an electric iron according to claim 7 in which said control dial support includes a bearing sleeve through which the conductors of said conductor cord pass.

9. In an electric iron according to claim 8 in which said cord support includes a pin extending upwardly through said bearing sleeve and a housing into which said cord extends swiveled to said pin above said control dial.

10. In an electric iron according to claim 7 in which said cord support includes an insulating housing into which said cord extends swiveled to said cover shell and lying above said control dial.

JUSTICE H. BEACH.
